BAG TRANSFORMER

Charles F. Sparks, St. Louis, Mo.

Application May 15, 1937, Serial No. 142,839

13 Claims. (Cl. 93—8)

This invention relates to bag transformers, and with regard to certain more specific features, to a method of and apparatus for converting a bag with one type of bottom into a bag having another type of bottom.

Among the several objects of the invention may be noted the provision of apparatus for operating upon a bag wherein a so-called "satchel" bottom which is unsymmetrically folded back against the body of the bag is converted into a symmetrically arranged bottom extension; the provision of apparatus of the class described in which the conversion or transformation is effected at a high speed and with simple machinery. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a side view of an empty bag of the type to be operated upon;

Fig. 2 is a view similar to Fig. 1 showing said bag after it has been operated upon;

Fig. 3 is a vertical section taken through the working parts of the transforming machine, showing a sector gear at one end of its oscillation;

Fig. 4 is a diagrammatic view of the machine showing said sector gear at the other end of its oscillation;

Fig. 5 is a view similar to Fig. 4 showing said sector gear in a mid-position and again advancing from the position shown in Fig. 4 to that shown in Fig. 3.

Fig. 6 is a view similar to Fig. 5 but on an enlarged scale showing the sector gear further advanced; and,

Fig. 7 is a view similar to Fig. 6 showing the sector gear after it has reversed movement and partly returned.

Similar reference characters indicate corresponding parts throughout the several views of the drawings.

Referring now more particularly to Fig. 1, there is shown at numeral 1 the tubular portion of a paper bag, which, as is shown in the art, has been folded to form a flat "satchel" bottom 3. This flat bottom 3 lies parallel to and against the flat tube 1, as shown.

A bag of the type shown in Fig. 1, if it be subject to a filling operation, particularly by means of pulvulent material, such as flour, tends to bulge but without opening up the bottom 3 and in fact tending to lock the same in unfilled position. It has therefore been the practice for the person who fills the bag to insert his hand and expand it before the material is inserted. This is an undeniable extra operation, and it is desirable that the bottom 3 be converted from the form shown in Fig. 1 to that shown in Fig. 2, wherein a crease is applied along the middle (as indicated at 5) so as to produce two areas in the bottom 3. These areas are indicated at numerals 7 and 9.

The area 9 already lies in the plane of the flat tubular portion 1, and it is desirable that the area 7 be rotated downwardly against the area 9 and ultimately that the areas 1 and 9 be positioned adjacent one another as closely parallel extensions from the flat tubular portion 1. Then the bag may be filled without pre-inserting the hand for bulging it, because the material as it descends through the tubular portion 1 strikes the central crease 5 and pushes it downwardly so as to flatten out the bottom from its folded position, said bottom remaining flatwise at right angles to the axial line of the bag. No locking against filling in at the bottom is then possible.

Referring now more particularly to Fig. 3, there is shown at numeral 11 a frame, which, at its upper portion, supports a cross shaft 13 on which is a group of pulleys 15. It will be understood that only one pulley 15 is in end elevation in Fig. 3, and that as many may be used endwise as is necessary to accommodate the width of the bag to be converted. A drive 17 continuously rotates the pulleys 15.

The pulleys 15 are grooved to receive belts 19 which also pass around grooves in pulleys 21. The belts 19 pass backwards over a relatively long roller 23 for purposes to be shown. It will of course be understood that the pulleys 15 may be integrated into one extensive roll with a plurality of belt-receiving grooves therein.

Arranged tangentially and sloping downwardly to the right and near the pulleys 15 is arranged a bag-receiving chute 25, the latter being hooked at the upper end to a cross shaft at 27 and supported at its lower end on a cross member 29. The cross member 29 is held in grooves 31 of holding plates 33. This chute, as is shown, is removable by unhooking it at 27 and dropping it downwardly to clear the grooves in plates 33.

The chute has, at a point adjacent the pulley 55

15, an opening 35 through which may pass a swinging resilient roller 37. The latter is mounted upon a shaft 39 supported between levers 41 on a cross shaft 43, the latter being under control of a lever 45 operated by means of a connecting rod 47 which reaches from the lever 49 of a lower bell-crank 51.

10 After almost complete clockwise rotation of the bell-crank 51, the roller 37 is sent through the opening 35 and forced against the belts which traverse the grooves around the pulleys 15 (see Fig. 4).

15 Pivoted to a cross-shaft 53 is a group of stop fingers 55 which are arcuate in form, and which are adapted to swing through an opening 57 at the lower end of the chute 25. The arcuate fingers are operated through a mechanism constituted by a lever 59 pivoted to a connecting rod 61 which reaches downwardly to said arm 49 on 20 the bell-crank 51. When the bell-crank 51 moves clockwise, the fingers 55 move clockwise and vice versa.

25 Adjacent the lower end of the chute 25 is rubber cross roller 62 against which is normally resiliently pressed a second rubber cross roller 63. The roller 63 is carried on a depending frame 65, which pivots from pins 67 and which carries at its lower end a spring support 69 around which is a spring 71 for normally forcing the frame 65 clockwise and to the left, so that the roller 63 is pressed against the roller 62.

30 At one end, the roller 62 is provided with a gear 73 which meshes with the sector 75 carried on an arm 77 forming part of said bell-crank 51. Depending from and pivoted to a cross shaft 79 is a frame-work 81 which carries receiving and folding plates 83 and 85. A stop 87 is located between the plates 83 and 85.

35 The lower folding plate 85 is slightly longer than the upper folding plate 83. The frame-work 81, upon which the folding plates are located, has pivoted thereto at 89 a connecting rod 91 which, through a pin-and-slot connection at 93, has lost-motion connection with the lever 49 of the bell-crank 51. The lost-motion connection is normally taken up by the upward pull of a spring 95 upon the frame-work 81, which has the effect of drawing up the connecting rod 91.

40 The bell-crank 51 rotates upon a cross shaft 94 and is driven by means of a crank 97, the latter being articulated to a connecting rod 99. The connecting rod 99 reaches from a suitable eccentric and has for its purpose the oscillation of the bell-crank 51.

45 Above the roller 63 is located a right-angular guide member 100 for purposes to be described.

50 Pivoted on a cross shaft 105 is a set of transformer fingers 107 having hooks 109 at their upper ends and normally drawn counterclockwise by the action of a spring 111. The clockwise action is limited by an extension 113 associated with the fingers 107 which strikes against a stop 115.

55 The operation of the device is as follows starting with the parts in the position shown in Fig. 3:

60 A bag of the type shown in Fig. 1 is dropped down the chute 25, with the flat "satchel" bottom 3 downward. Therein it is stopped by the stop fingers 55 until a preceding bag clears from 70 between rollers 62 and 63. At this instant the bell-crank 51 has started to rotate clockwise, thus, through the sector 75, rotating the roller 62 counter-clockwise and clearing the preceding bag and sending the fingers 55 clockwise from the 75 opening 57. The fingers 55 start to recede from

the opening 57 but do not do so entirely before the bottom edge of the bag strikes them. These fingers 55 function to prevent the bags from descending too far at the wrong time. Thus they are in effect timers for entry of the bags into 5 the succeeding operations.

65 It should be noted in respect to Fig. 3 that the fingers 55 when completely extended through the opening 57 also form with the guide member 100 a passage 101 for outgoing transformed bags as 10 will be described.

70 As the sector 75 moves clockwise from the Fig. 3 position to the Fig. 4 position, the rollers 62 and 63 rotate to discharge the preceding bag and assume the positions to receive the bag 15 which is released in the chute 25 by the fingers 55. But just as the fingers 55 release the bag the swinging roller 37 is driven to press the upper end of the bag against the belts 19. Thus for an instant the bag is positively forced downwardly toward and between the rollers 62 and 63. If the timing of the roller 37 be inexact no 20 harm is done because of the timing action of the fingers 55. Under such circumstances the bag may buckle away from the chute 25. But as 25 soon as the fingers 55 release it, it again straightens out.

25 In Figs. 4 and 5 is shown the fact that as the sector 75 advances to the left, or counter-clockwise, the bottom of the incoming bag is driven 30 down through the rollers 62 and 63 with the bottom interposed between the folding plates 83 and 85. At this time the folding plates are about to recede from beneath the rollers 62 and 63, because the lost motion of the pin-and-slot connection 93 35 has been taken up. At this time also the roller 37 has been drawn from the belts 19, so that the upper end of the bag 1 is free to swing to the right against the guide member 100. This rightward 40 swing of the upper end of the bag 1 is aided by the counter-clockwise movement of the fingers 55 45 which is taking place at this time and by the movement of the belts on the underside of the pulleys to move the upper edge of the bag to the right. It is to be understood that as between Figs. 3 and 4, 45 motion of the sector 75 has reversed; whereas between Figs. 4 and 5 it has not.

50 It will also be understood that the folding plates 83 and 85 have gone up into position shown in Fig. 5 just under the tangent point between the 50 rollers 62 and 63 and into a position to receive the lower edge of the bottom 3 as sent through said rollers 62 and 63, the bottom of the edge of the bag having come into contact with the stop 87.

55 As the bell crank 51 approaches its ultimate left-hand position under action of the eccentric rod 99 (Fig. 6) the folding plates 83 and 85 descend to accommodate the length of the bag which must necessarily pass between rollers 62 and 63 in order to bring the flat bottom 3 entirely below said rollers.

60 The transformer hooks 109 are positioned in Fig. 6 in the maximum counter-clockwise position that they will assume with the stop 113 against the pin 115. Inasmuch as the folding plates 83 65 and 85 are at this time swinging to the left, the bag 1 is given a curved form which tends to spring or angle the plane portion 7 away from the remainder of the bag and spring it against said hooks 109.

70 Then, as the parts move from the position shown in Fig. 6 to their ultimate positions, the area 7 of said bottom has its upper edge slip under the properly positioned hooks 109 of the transformer fingers 107.

Finally, the bell-crank having reached its ultimate left-hand position, starts the return clockwise. This again forces up the folding plates 83 and 85 toward the rollers 62 and 63. This causes the area 7 of the bottom 3 of the bag to be caught by the transformer hooks 109 in the manner shown in Fig. 7. The relative rotation of area 7 is clockwise, thus making the crease 5 and bringing the area 7 down toward the area 9. The upper edge of the lower holding plate 85 effects the initial crease which is later finished by movement of the adjacent and parallel areas 7 and 9 through the rollers 62 and 63 which are this time rotating oppositely to the rotation shown in Fig. 6. The opposite rotation is due to the then clockwise motion of the sector 75.

It should be understood that each area 7 and 9 has pasted multi-layers therein and that therefore each is relatively thick so that the action shown in Fig. 7 takes place, namely, the area 7 forces the transformer fingers 107 clockwise against the tension of spring 111. Thereafter the transformer fingers hold the area 7 as the bag is pushed upwardly and finally the areas 7 and 9 become adjacently located and pass upwardly between the rollers 62 and 63.

As shown above, the bag passes downwardly to the rollers 62 and 63 and is drawn to the left thereunder, as shown in Fig. 4, and that the upper portion will naturally swing toward the right. It swings against the stop plate 100. Then, as the bag moves upwardly under the action as described, and the folded planes 7 and 9 come together and pass through the rollers 62 and 63, the position of the fingers 55 is such as to form a guide passage for them between said plate 100 and fingers 55.

The upper edge of the bag is then forced against the left of the roller 23 and under the belt 19 to be fed laterally and to the right from the machine, transformed as shown in Fig. 2, except that the areas 7 and 9 are flatter against one another. In Fig. 2 these areas are slightly separated for clarity.

The lost-motion connection between the connecting rod 91 and the lever 49 assures that the folding plates 83 and 85 remain in position just below the rollers 62 and 63 until they have received the lower edge of the bag. Thereafter, the folding plates are drawn down with the bag bottom therein.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A bag transformer comprising means adapted to receive empty bags which have bottoms lying against one side and partly extending from the body of the bag, reversible means adapted to draw in said bag, bending means beyond said reversible means adapted to receive the extending portion of said bag bottom and to bend the bag to cause the other portion of said bottom to angle out of the plane of the bag, said reversible means withdrawing the bag from said bending means, and means to hold said angled portion of said body as the bag reverses movement, whereby said angled portion is folded against said extending portion.

2. A bag transformer comprising a chute adapted to receive empty bags which have bottoms partly lying against one side and partly extending from the body of the bag, reversible rotating means adapted first to draw said bag inwardly, oscillating means beyond said rotating means adapted to receive the extending portion of said bag bottom and to oscillate to bend the bag to angle a portion of said bottom out of the plane of the bag, means for reversing said reversible rotating means to withdraw the bag from said oscillating means, and means to hold said angled portion as the bag reverses movement, whereby said extending portion is folded against said portion of the body which is held in the oscillating means.

3. A bag transformer comprising a chute adapted to receive empty bags each of which has a bottom part lying against one side and a bottom part extending from the body of the bag, reversible rotating means adapted to draw said bag downwardly, oscillating means below said rotating means adapted to receive the extending part of said bag bottom and to oscillate laterally to bend the bag to cause the other portion of said bottom to angle out of the plane of the bag, means for reversing said reversible rotating means to withdraw the bag from said oscillating means, and means to hold said angled portion of said body as the bag reverses movement, whereby said angled portion is folded against said portion of the bottom which is held in the oscillating means, and movable means adapted to support incoming bags in said chute to time their advance for proper delivery to said reversible rotating means.

4. A bag transformer comprising a chute adapted to receive bags each having a bottom with one portion lying against one side of the bag and another portion extending therefrom, reversible rotating means adapted to draw said bag downwardly, oscillating means below said rotating means adapted to receive the extending portion of said bag bottom and to oscillate to bend the bag to cause the other portion of said bottom to angle out of the plane of the bag, means for reversing said reversible rotating means thereby to withdraw the bag from said oscillating means, means to hold said extending portion of said body as the bag reverses movement, whereby said angled portion is folded against said portion of the body which is held in the oscillating means, and movable means adapted to support incoming bags in said chute to time their further advance for proper delivery to said reversible rotating means, said timing means also functioning as a guide means for the bag as it returns from said reversible rotating means.

5. A bag transformer comprising a chute adapted to receive bags each having a bottom with one portion lying against one side of the bag and another portion extending therefrom, reversible rotating means adapted to draw said bag downwardly, oscillating means below said rotating means adapted to receive the extending portion of said bag bottom and to oscillate to bend the bag to cause the other portion of said bottom to angle out of the plane of the bag, means for reversing said reversible rotating means thereby to withdraw the bag from said oscillating means, means to hold said extending portion of said body as the bag reverses movement, whereby said angled portion is folded against said portion of the body which is held in the oscillating means, movable means adapted to support incoming bags

in said chute to time their further advance for proper delivery to said reversible rotating means, said timing means also functioning as a guide means for the bag as it returns from said reversible rotating means, and means on the inlet side of said reversible means adapted to receive transformed bags to eject them from the machine.

6. A bag transformer comprising a chute 10 adapted to receive bags each having a bottom with one portion lying against one side of the bag and another portion extending therefrom, reversible rotating means adapted to draw said bag downwardly, oscillating means below said rotating 15 means adapted to receive the extending portion of said bag bottom and to oscillate to bend the bag to cause the other portion of said bottom to angle out of the plane of the bag, means for reversing said reversible rotating means thereby 20 to withdraw the bag from said oscillating means, means to hold said extending portion of said body as the bag reverses movement, whereby said angled portion is folded against said portion of the body which is held in the oscillating 25 means, movable means adapted to support incoming bags in said chute to time their further advance for proper delivery to said reversible rotating means, said timing means also functioning as a guide means for the bag as it returns from 30 said reversible rotating means, and means adjacent said guide means adapted to grip the returning bag to deliver it from the machine, said delivery means having a component adjacent said chute, and a timed presser member adapted 35 to cooperate therewith to intermittently effect a forcing of the bags from the chute to said reversible rotary means when said timing means permits.

7. Bag converting apparatus comprising an 40 inlet means for bags having one portion lying against the side of the bag and another extending downwardly therefrom, comprising a pair of rollers resiliently pressed together, means for reversibly rotating said rollers, means for intermittently feeding bags into said rollers whereby 45 said bags are partially drawn through said rollers, said means for reversing the rollers being operative to reverse before the bag has passed entirely through said rollers, and means adjacent the 50 rollers adapted to receive the extending portion of said bottom and to move it laterally with respect to the body of the bag whereby the other portion of the bottom is angled from said body of the bag, and means for holding said angled 55 portion of said bottom while the other portion rises through said rollers whereby the two portions of the bottom become positioned adjacently as they again pass through said rollers.

8. Bag converting apparatus comprising an 60 inlet means for bags each having one portion lying against the side of the bag and another extending downwardly therefrom, comprising a pair of rollers resiliently pressed together, means for reversibly rotating said rollers, means for intermittently feeding bags into said rollers whereby 65 they are drawn in, said means for reversing the rollers being operative to reverse before the bag has passed entirely through said rollers, oscillating means adjacent the rollers adapted to receive the extending portion of said bottom and to move it laterally with respect to the body of the bag whereby the other portion of the bottom is angled

free of said body of the bag, and means for holding said angled portion of said creased portion of the bottom while the other portion rises through said rollers by reason of the return of said oscillating means and reversal of the rollers, whereby the two portions of the bottom become positioned adjacently as they again pass through said rollers. 5

9. A transforming apparatus comprising a downwardly sloping chute, a pair of rollers at the 10 base thereof, means for resiliently pressing said rollers together, means for reversibly rotating said rollers, timing means for intermittently sending bags to said rollers to be fed therein under action of rotation, means below the rollers 15 adapted to receive one portion of the bottom of the bag and to retract it as said rotation continues and to reverse its direction of movement as said direction of rotation is reversed, and means for holding another portion of said bottom 20 as said direction of rotation is reversed whereby the two portions of said bottom are brought together to be pressed between said rollers after the direction of rotation has been reversed. 25

10. The method of transforming a bag having a flat bottom with a portion adjacent the side of the bag and a portion extending therefrom, into a bag with the bottom having two parallel portions extending therefrom, comprising, pressing 30 the bag from opposite sides and moving it in a given direction, deflecting the advancing edge of said bag whereby the portion of said bottom adjacent the body of the bag is made to angle from said body, and reversely moving said bag 35 from its advanced, deflected and angled position while holding said angled portion whereby said last-named portion rotates against the said extending portion of said bottom.

11. The method of transforming a bag having 40 a bottom with a portion adjacent the side of the bag and a portion extending therefrom, into a bag with the bottom having two parallel portions extending therefrom, comprising, moving the bag bottom first in a given direction, deflecting the 45 advancing bottom edge of said bag whereby the portion of said bottom adjacent the body of the bag is made to angle from said body, and reversely moving said bag from its advanced and deflected position while holding said angled portion 50 of the bottom.

12. The method of transforming unfilled and flat bags each having a flat bottom with one portion adjacent the flat sides of the bag and one portion extending therefrom, comprising moving 55 each bag in one direction, reversing the movement of said bag, holding the said adjacently located portion to interfere with its reverse movement whereby it becomes rotated adjacently to the plane of said extending portion. 60

13. The method of transforming unfilled and flat bags each having a flat bottom with a portion adjacent the flat sides of the bag and a portion extending therefrom, comprising moving each bag in one direction, deflecting the same to cause said 65 portion of the bottom which was adjacent the side to be angled therefrom, reversing the movement of said bag, holding the edge of said angled portion to interfere with its reverse movement whereby it becomes moved into position adjacent 70 to the plane of said extending portion.

CHARLES F. SPARKS.
